ICE TRAY

Homer E. Rosebrook, Greenville, Mich., assignor to Hupp Corporation, Cleveland, Ohio, a corporation of Virginia

Filed June 11, 1964, Ser. No. 80,361

Term of patent 14 years

(Cl. D67—3)

FIG. 4

FIG. 5

FIG. 6

FIGURE 1 is a top plan view of an ice tray, embodying my new design;

FIGURE 2 is an elevational view taken from one end thereof, the other end being essentially the same as the end shown;

FIGURE 3 is a fragmentary cross sectional view taken on line 3-3 of FIGURE 1;

FIGURE 4 is a bottom plan view thereof;

FIGURE 5 is an elevational view taken from one side thereof, the other side being substantially the same as the side shown; and

FIGURE 6 is a fragmentary cross sectional view taken on line 6-6 of FIGURE 1.

I claim:

The ornamental design for an ice tray, substantially as shown and described.
